FOOTER BAR FOR FULL FASHIONED
HOSIERY MACHINES

Robert A. Folkman, Concord, N. C., assignor to
Hugh Grey Hosiery Company, Concord, N. C.,
a corporation of North Carolina

Application October 5, 1940, Serial No. 359,826

2 Claims. (Cl. 66—149)

This invention relates to a footer bar for full fashioned hosiery machines and more especially to means for applying tension to the leg portion of a stocking while the foot portion is being knitted thereto.

It is usual practice to knit the leg portion of a full-fashioned stocking on a machine called a legger, and then to transfer the leg portion to a machine called a footer for knitting the foot portion. When this transfer is effected, it is necessary to provide a tension and take-up mechanism to maintain the proper tension on the loops and also to withdraw the stocking from the knitting needles as the foot portion is knitted. As a general rule, the material from which full fashioned hose are made is very sheer, thus making it easily damaged. Even though a thread in the stocking may not be broken, the appearance and quality may be adversely affected, by distorting the loops as a result of applying improper tension during knitting. A typical example of the conventional tension device is shown in Patent Number 1,763,280 of June 10, 1930. It is here seen that a plurality of tension hooks engage the stocking, thereby concentrating all of the stress at a few points. As a result, the loops at the hooks will be distorted and the appearance of the finished hose will be marred.

It is therefore an object of this invention to provide a tension and take-up device of the character described which is adapted to clamp the leg portion of the stocking over a wide area so that the stresses will be more equally distributed and hence less distortion will take place. Specifically, the invention comprises a bar under tension which has hooks for engaging the heel gussets of the stocking and which also has a clasp engaging the intermediate leg portion. The heel gussets are usually made of heavier material than the leg portion and therefore will not be easily damaged by the hooks, but since the leg portion is usually made of a sheerer material it is preferable to use a clamp at this location.

It is another object of this invention to provide an open ended clamping means of the class described, which is adapted to simultaneously engage both sides of the leg portion and which extends transversely of the stocking leg substantially the width thereof. By having an open end to the clamp the leg portion can be easily inserted therein or removed therefrom at one operation with one hand without any likelihood of damage to the stocking.

Some of the objects of the invention having been stated, other objects will appear as the de-

scription proceeds, when taken in connection with the accompanying drawing, in which—

Figure 1 is an isometric view of a portion of a full fashioned hosiery machine commonly called a footer, showing my improved tension device associated therewith;

Figure 2 is a transverse vertical sectional view taken along the line 2—2 in Figure 1;

Figure 3 is a longitudinal vertical sectional view taken along the line 3—3 in Figure 1.

Referring more specifically to the drawing, the numeral 10 denotes a conventional knitting head of a full-fashioned hosiery machine said machine having a table 11, tension roller 12, control rod 14, and guard rod 15. As heretofore stated, full-fashioned hosiery is knitted by a machine called a legger and then transferred to a machine called a footer to knit the leg and foot portions respectively. In the present embodiment of the invention, the leg portion is designated by the reference character 16. The leg portion is shown on a machine called a footer and has knitted thereto suitable heel gussets 17 which extend from opposed edges thereof. These heel gussets are adapted to be engaged by hoods or work engaging elements 18 which in turn, are fastened as at 19 to the opposed end of a bar 20, said bar having a strap 21 secured thereto as at 23. It will be noted that the other end of the strap 22 is secured as at 24 to tension roller 12, and that the intermediate portion of the strap has a slack portion 21a therein which is produced by a plurality of tension springs 25. These tension springs furnish the necessary elasticity to the strap so that the heel gussets 17 will have the proper tension applied thereto during a knitting operation. As the foot portion of the stocking is knitted, the tension roller 12 winds the strap 21 therearound so that an even tension will be maintained upon the foot loops at the knitting head.

As heretofore stated, the heel gussets 17 are reinforced more than the leg portion, and therefore the likelihood of damage by the hooks 18 is not so great as would be the case if hooks were used upon the leg portion. In order to provide means for exerting the necessary tension on the leg portion of the stocking without causing any damage thereto, a suitable S-shaped clamp 26 is secured to the upper portion of the bar 20 by any suitable means such as screws 27.

It will be seen by referring to Figures 1 and 2 that the clasp or clamp comprises a resilient metallic bar which is reversely bent two times, thus forming three superposed transverse portions

specifically designated by reference characters 28, 29 and 30. The transverse portion 28 is employed as a base which, in turn is secured to the bar 20 by screws 27; whereas the portions 29 and 30 are employed for resiliently engaging the opposed sides of the intermediate leg portion 16 of the stocking. The portions 29 and 30 are preferably made of a suitable resilient material such as spring steel or a suitable rust-proof alloy so that the inherent resiliency therein will normally tend to force the proximate faces of these two portions together and to clamp the stocking when it is therebetween.

Also it is seen that the portions 29 and 30 extend substantially the width of the leg portion of the stocking thereby making it easy to insert or remove the leg portion within the clamp. The ease of insertion or removal is facilitated by having the portions 29 and 30 flared downwardly and upwardly respectively as at 32 and 33. If the leg portion of the stocking happens to be a good deal wider than the clamp it is desirable to bunch or crinkle the leg portion substantially an equal amount throughout its width and insert the crinkled or bunched portion between portions 29 and 30. The crinkled work-piece will make the clamping of the portions 29 and 30 more effective because there will be a greater thickness of material therebetween.

Another very decided advantage of the present device is the resilient mounting of the clamping portions 29 and 30. For example, the portions 29 and 30 are mounted in spaced relation to the bar 20 and do not rest directly thereon because these portions are connected by a single thickness of the clamp bar as at 32 to the supporting bar 20.

In the drawing and specification there has

been set forth a preferred embodiment of the invention and although specific terms are employed, they are used in a generic and descriptive sense only, and not for purposes of limitation, the scope of the invention being set forth in the appended claims.

I claim:

1. Means for supporting the leg and heel gussets of an incomplete full fashioned stocking while the foot is knitted comprising a footer bar having means on each end thereof for engaging the heel gussets, and a resilient member secured to the footer bar, said resilient member comprising a bar doubled upon itself and forming an open ended slot therebetween into which the leg of the stocking can be placed to be clampingly held while the foot portion of the stocking is knitted, and means for securing the lower leg of the resilient member to the footer bar.
2. In a footer bar for full fashioned knitting machines a bar having hooks on each end, for engaging the heel gussets of a leg portion of a stocking, means for clampingly holding the leg portion of the stocking comprising a member extending transversely of the stocking and longitudinally of the bar and being secured to the bar, said member being reversely bent to lie above and in close proximity to that portion secured to the bar, said member being again reversely bent into engagement with the upper surface of the second leg of the member and to be resiliently held in engagement with the second leg of said member, the free end of the upper leg of said member being bent upwardly to facilitate the placing of the leg of the stocking below the upper portion of said resilient member.

ROBERT A. FOLKMAN.
